UNITED STATES PATENT OFFICE.

WILLIAM JOHN SANKEY, JR., OF HATCHECHUBBEE, ALABAMA.

FIRE EXTINGUISHER FOR AIRPLANES.

1,419,311.

Specification of Letters Patent. Patented June 13, 1922.

Application filed May 16, 1921. Serial No. 469,844.

To all whom it may concern:

Be it known that I, WILLIAM J. SANKEY, Jr., a citizen of the United States, and a resident of Hatchechubbee, in the county of Russell and State of Alabama, have invented 5 certain new and useful Improvements in Fire Extinguishers for Airplanes, of which the following is a specification.

My invention relates to airplanes, dirigible balloons and the like, and has particular 10 reference to the fuselage therefor, the purpose of my invention being the provision of a fuselage having means for extinguishing any and all conflagrations occurring in the 15 engine and fuel compartments during flight and thereby preventing the usual disastrous results and permitting of the safe landing of the airplane.

It is also a purpose of my invention to 20 provide a fire extinguisher which includes a plurality of gates controlling draft openings formed in the fuselage, and means for maintaining the gates in open position which is manually releasable to effect the simultaneous 25 and positive closing of the draft openings, thus hermetically sealing the fuel and engine compartments and preventing the further supply of air thereto so as to positively effect the extinguishing of the 30 flames.

I will describe one form of fuselage, and one form of fire extinguisher embodying my invention and will then point out the novel features thereof in claims.

35 In the accompanying drawings:

Figure 1 is a view showing in perspective the front end portion of the fuselage having applied thereto one form of fire extinguisher embodying my invention.

40 Figure 2 is a fragmentary horizontal sectional view of a portion of the front end of the fuselage shown in Figure 1.

Figure 3 is a vertical sectional view taken on the line 3—3 of Figure 1.

45 Figures 4 and 5 are plan views of the fire extinguisher in active and inactive positions, respectively, with the fuselage shown diagrammatically.

Similar reference characters refer to similar parts in each of the several views.

50 Referring specifically to the drawings and particularly to Figure 1, I have here shown a conventional form of fuselage for airplanes having at its extreme forward end an engine compartment designated at E, and 55 a fuel compartment designated at F di-

rectly in the rear of the engine compartment, all as clearly shown in Figure 4. The fuselage includes side walls 15 and 15^a formed with draft openings 16 and 16^a, a solid top 60 wall 17 suitably secured in spanning position with relation to the engine and fuel compartments, and a front wall 18 formed with a multiplicity of openings 19 which cooperate to form a front draft opening. 65 It will be understood that the side draft opening 16 and the front draft opening 19 cooperate in permitting the circulation of air through the engine compartment in effecting the cooling of the engine, with the air 70 travelling in the paths indicated by the arrows in Figures 2 and 5.

The operator's seat is designated at S in Figure 1 and as is customary is directly in the rear of the fuel compartment.

75

The fire extinguisher forming the subject matter of my invention of necessity includes certain portions of the fuselage, but essentially consists of side gates G and G' and a front gate G², all of which are adapted to be maintained in open position by latching devices L, L' and L², respectively, and moved to closed position by means of springs when a cam latch actuating means is operated by the driver. The side gates 80 G and G' control the draft openings 16 and 16^a, and as shown in Figure 1 are supported for outward swinging movement by means of hinges 20 secured to the side walls 15 and 15^a and to the front ends of the 90 gates. This particular manner of mounting the gates facilitates the circulation of air through the engine compartment as will be readily understood by an observation of Figure 5. Each gate G or G' is normally urged to closed position by means of a 95 spring 21 secured at one end to an angle plate 22 secured to the fuselage and at the other end to a flange 23 formed on the upper edge of the gate. Each gate is also formed 100 with a flange 24 on the lower edge thereof, the purpose of the two flanges 23 and 24 being to provide the necessary reinforcement for the gate. The front gate G² comprises 105 a rectangular sheet of metal mounted for vertical sliding movement in guide plates 25 secured to the front wall 18 in the manner clearly shown in Figures 1 and 2. The plate forming the gate G² is provided with openings 26 corresponding in number and 110 position to the openings 19 so that when the gate is in open position as shown in

Figures 1 and 2 the two sets of openings are in registration with each other thus allowing the passage of air into the engine compartment. However, when the gate G^2 is lowered to closed position as shown in Figure 3, the two sets of openings are out of registration with each other thus forming a seal against the passage of air to the engine compartment. The gate G^2 is normally maintained in closed position by means of springs 27 secured to lips 25^a formed on the lower ends of the guide plates 25. The upper ends of the springs are secured to the hooked ends of rods 28 depending from 15 and secured to a flange 29^a formed on a latch plate 29.

The latching device L^2 for maintaining the gate G^2 in open position against the tension of the springs 27 comprises in the present instance a latch plate 29, a latching finger 30 and a releasing member 31. The latch plate 29 is secured to the upper end of the gate G^2 in the manner clearly shown in Figures 1 and 3 with its lower edge constituting a projection which is adapted to be engaged by a finger 30 for holding the gate against downward movement. The latching finger 30 depends from a bar 32 secured to the front wall 18, such finger being formed of resilient material and having its lower end inturned so as to be normally disposed in the path of movement of the plate 29. The releasing member 31 is disposed between the plate 29 and the finger 30 and is mounted for oscillatory movement so as to force the finger outwardly to disengage the lower edge of the latch plate 29 thereby permitting the springs 27 to draw the gate to closed position. The gate G^2 is adapted to be latched in open position by manually lifting the gate through the medium of the flange 29^a, the resiliency of the latch finger causing the same to engage the lower edge of the latch plate when the gate has been lifted sufficiently, as will be understood.

The latching devices L and L' are of the same construction so that a description of one will suffice for both. The latching device L or L' comprises in the present instance a substantially U-shaped yoke 33 mounted for swinging movement with a bracket 34 secured to the side wall 15 or 15^a at a point in the rear of the draft opening 16 or 16^a. The vertical portion of the yoke 33 is sufficiently wide to allow the free end of the gate to repose thereon when the latter is in open position, lugs 35 being formed on the yoke for limiting the inward movement thereof with respect to the gate when the latter is in open position. Because of the mounting of the yoke 33, it will be clear that it can be swung rearwardly from the latching position shown in Figure 5 to the released position shown in Figure 4, so that the gate automatically swings to closed posi-

tion under the action of the spring 21. It is to be understood that in latching the gate in open position, it is manually swung outwardly and the yoke properly positioned so as to engage the free end of the gate in the manner shown in Figure 5.

The mechanism for actuating the several latching devices comprises a shaft 37 journaled in the fuselage at a point directly in front of the operator's seat S, such shaft being provided with an actuating handle 38 disposed in convenient relation to the operator occupying the seat S. The opposite ends of the shaft 37 project from the opposite sides of the fuselage as clearly shown in Figures 4 and 5, and these projected ends are formed with cranks 39 which are operatively connected to the yokes 33 through rods or cables 40 and rings 41. The yokes in turn are operatively connected to cranks 42 formed in the opposite ends of the shaft 43 through the medium of rods or cables 44 having turnbuckles 45 for effecting a longitudinal adjustment of the rods. These rods 44 are connected to the rings 41 at one end and to U-shaped links 46 at the other, the latter being mounted on the free ends of the cranks 42. The shaft 43 is journaled in ears 47 formed on plates 48 secured to the front wall 18. This shaft 43 constitutes an integral part of the releasing member 31 so that by rotation of the shaft an actuation of the releasing member is effected to move the latching finger 30 to released position.

From the foregoing mechanism it will be clear that the operator occupying the seat S can readily effect the simultaneous closure of all of the gates by pulling the handle 38 from the position shown in Figure 5 to that shown in Figure 4 thereby rotating the shaft 37 to cause the rearward movement of the cranks 39 and thus exert a rearward pull on the yokes 33 to cause the latter to disengage the gates G and G' . With the rearward movement of the yokes, the cranks 42 are likewise actuated thus rotating the shaft 43 to cause the releasing member to move the latching finger 30 to disengaging position with respect to the latch plate 29.

In practice, the several gates are moved to open position before the takeoff of the airplane thus providing of the necessary draft through the engine compartments to effect a cooling of the engine during flight. Should a conflagration occur in either the engine compartment or the fuel compartment, the operator immediately pulls the handle 38 thus causing all of the gates to close simultaneously and thereby cutting off a further supply of air to the engine and fuel compartments. As soon as the oxygen trapped in the fuselage is consumed, the flames will be extinguished thus allowing the safe landing of the airplane and elimi-

nating the possibility of the fuel tank exploding or any injury to the operator as a result of this conflagration.

Although I have herein shown and described only one form of fuselage and one form of fire extinguisher embodying my invention, it is to be understood that various changes and modifications may be made herein without departing from the spirit 10 of the invention or the spirit and scope of the appended claims.

What I claim is:

1. In combination, a fuselage including engine and fuel compartments having draft 15 openings in the walls thereof, gates controlling said openings, releasable means for maintaining the gates in open position, and manually operable means for simultaneously closing all of the gates whereby the 20 further supply of air to the compartments is prevented.

2. In combination, a fuselage having draft openings formed in the front and side walls thereof, horizontally mounted gates 25 controlling the side openings, a sliding gate controlling the front opening, means for normally urging the gates to closed position, latching devices for maintaining the gates in open position against the action 30 of said urging means, and manually operable means for simultaneously actuating all of said latching devices to effect the simultaneous release of all of said gates.

3. In combination, a fuselage having 35 draft openings formed in the front and side walls thereof, horizontally mounted gates for controlling the side openings and a sliding gate for controlling the front opening, means for normally urging the 40 gates to closed position, latching devices for the side gates comprising swingingly mounted yokes, a latching device for the front gate comprising a latch plate, a resilient latching finger and a releasing member, 45 and manually operable means for simultaneously actuating said releasing member and said yokes in such manner as to cause said latching finger to disengage said latch plate and said yokes to disengage said 50 gates whereby said urging means functions to simultaneously close all of the gates.

4. In combination, a fuselage having side and front draft openings, horizontally 55 mounted gates for controlling the side

openings, a sliding gate for controlling the front opening, springs for normally urging the gates to closed position, latching devices comprising swingingly mounted yokes for maintaining the side gates in open position, and projections carried by the yokes for limiting the movement of the gates and yokes, a latching device for the sliding gate comprising a latch plate carried by the gate, a resilient latching finger engageable with the plate for maintaining the gate in open position, and a releasing member adapted to engage the finger for moving the latter to released position with respect to said plate, and manually operable means for actuating all of said latches comprising a shaft operatively connected to said yokes, a second shaft supporting said releasing member, means for operatively connecting the first shaft with the 75 second shaft, and a handle for actuating the first shaft whereby said yokes are moved to disengaged position with respect to the side gates and said releasing member is caused to actuate said latching finger. 80

5. In combination, a fuselage having draft openings in the walls thereof, closures for said openings, said fuselage being substantially air-tight when said closures are in position to close said draft openings, 85 means for urging said closures to position to close said openings, latching mechanism for said last named means whereby said closures may be releasably maintained in open position, and releasing mechanism for 90 said latching mechanism.

6. In combination, a fuselage having draft openings in the walls thereof, closures for said openings, said fuselage being substantially air-tight when said closures are 95 in position to close said openings, and the flow of air through said draft openings being controlled in accordance with the position of said closures, and operating means for said closures. 100

7. In combination, a fuselage including a front wall and side walls, said front wall and said side walls having draft openings, closures for said openings, said fuselage being substantially air-tight when said 105 closures are in position to close said draft openings, and operating means for said closures.

WILLIAM JOHN SANKEY, JR.
